UNITED STATES PATENT OFFICE.

JOHN T. DRUFVA, OF LONG MEADOW, MASSACHUSETTS, ASSIGNOR TO HENRY HYMAN & CO., INC., OF NEW YORK, N. Y., A CORPORATION OF NEW YORK.

PORTABLE ELECTRIC LIGHT.

Application filed May 28, 1919. Serial No. 300,399.

To all whom it may concern:

Be it known that I, JOHN T. DRUFVA, a citizen of the United States, and a resident of Long Meadow, in the county of Hampden and State of Massachusetts, have invented certain new and useful Improvements in Portable Electric Lights, of which the following is a specification.

The invention pertains more particularly to the character of electric flashlights to be held in the hand and lighted, as occasion may require, by the manual movement of a slide or other switch device applied upon the exterior casing of the flashlight.

My invention resides more particularly in a novel arrangement and construction of parts, including means for completing the circuit between the lamp and battery, which obviates the accidental circuiting of the lamp by contact with metal articles, such as might arise when a flashlight, otherwise constructed, is placed in a box of tools.

The invention will be fully understood from the detailed description hereinafter presented, reference being had to the accompanying drawings, in which:

Fig. 1 is a central vertical section through a portable electric light embodying my invention;

Fig. 2 is a corresponding section through the casing of the flashlight, taken at a right angle to the section of Fig. 1;

Fig. 3 is a sectional view through the lower end of the flashlight, taken on the dotted line 3-3 of Fig. 1, and

Fig. 4 is a transverse section through a portion of the flashlight, taken on the dotted line 4-4 of Fig. 2.

In the drawings, 10 designates a tubular casing, preferably of fibre or other insulating material, 11 a plural cell battery therein, 12 a wrapping of insulating material on said battery, 13 a screw cap of customary construction closing the lower end of said casing, 14 a conducting spring engaging the negative pole of the battery, 15 a threaded sleeve secured to the rear end of the casing 10 and receiving the threaded portion of the customary cap 13, 16 a sleeve secured to the forward end of the said casing 17, a customary collar or sleeve screwed upon the sleeve 16, 18 a customary lens held in position by the aforesaid collar or sleeve 17, 19 a customary reflector within the forward end 55 of the casing 10 and supported upon the outer end thereof below said lens, and 20 a miniature electric lamp of known character having its terminal sleeve 21 screwed into the usual threaded sleeve 22 of said reflector, the other terminal 23 of the lamp being held 60 in engagement with the positive pole 24 of the battery by means of the spring 14. The parts specifically referred to by reference numerals hereinbefore are, with the exception of certain details hereinafter mentioned, 65 of customary arrangement and construction.

In accordance with my invention I provide a construction to avoid the accidental circuiting of the battery and lamp, and hence there are features of construction presented by me which enter into combination with prior art features in the production of the completed article of manufacture and which enhance the value and desirability of the same, these new features having to do 70 with the making and breaking of the circuit and also with the avoidance of short-circuiting or accidental circuiting of the current.

In accordance with my invention I secure upon the exterior side of the casing 10, by 75 means of eyelets 25, 26, a housing or escutcheon, of box-like formation, 27 having laterally extending wings 28, 29, respectively, and within the escutcheon or housing 27 I locate a spring switch 30 which is of 80 known type and is connected with a thumb-piece or slide 31 and engaged by a push-button 32, the push-button 32 being utilized for momentary or short period lighting of the lamp, and the slide 31 being 85 adapted for use when a more continuous lighting of the lamp is desired. One wing of the housing or escutcheon 27 has secured to it the lower end of a conducting strip 33 which is engaged at its upper end by an 90 inwardly turned flange 34 on the threaded sleeve 16 on which the customary flange of the reflector 19 rests. The conducting strip 33 laps over upon the upper end of the casing 10 and is held down on the upper edge 95 of said casing by the sleeve 16. The upper edge flange on the reflector 19 rests upon the flange 34 of the sleeve 16, and hence one terminal of the lamp 20 is, through the reflector 19 and sleeve 16, always in electrical 100 connection with the conducting strip 33 which is at the inner side of the casing 10 and extends to and is in electrical engagement with the wing 29 of the housing or escutcheon 27.

The cap 13 at the lower or rear end of the casing 10 has applied on its upper surface an insulating disk 35, and over this disk 35 is secured a metal disk 36 having 5 a lower cup-like central portion 37 and an elevated encompassing annular ring 38. The disk 36 is mounted upon an insulating disk 39 which is placed upon the insulating disk 35 and connected with the depressed or cup-like portion 37 of said disk 36 by means of 10 a rivet or eyelet 40 whose lower end is housed within an opening in the disk 35 and spaced above the lower end of the cap 13, as shown in Fig. 1, whereby the disk 36 becomes insulated from the cap 13 and the rivet or eyelet 40 becomes insulated from the lower end of the cap 13, while at 15 the same time serving to retain the disk 36 rigidly in place. The flange 38 of the metal disk 36 is formed with upwardly extending loops 41 through which the end portion of the lower coil of the spring 14 is inserted, as shown in Fig. 3, for the purpose of holding 20 said spring 14 rigidly in position and in electrical connection with the disk 36. The disk 36 is in electrical connection 25 through the spring 14 with the negative pole of the battery 11, but, as clearly represented, is insulated from the rear closing cap 13. The insulating disk 35 affords an 30 insulating space for the lower end of the eyelet or rivet 40, and the insulating disk 39 serves to insulate the eyelet or rivet 40, disk 36, spring 14 and the negative pole 35 of the battery from the cap 13 and sleeve 15. The circuit from the negative pole of the 40 battery is through the spring 14 and disk 36 to the conducting strip 42, which is engaged at its lower end by the edge portion of the disk 36 and extends upwardly along the inner walls of the casing 10 to a point above the lower end of the conducting strip 33 and into alignment with the upper portion 45 of the chamber of the housing or escutcheon 27, at which point said conducting strip 42 is secured to the casing 10 by means of an eyelet or rivet 43 whose inner end engages the strip 42 and whose outer end is protected by or concealed within the housing or escutcheon 27, as shown in Fig. 1. The eyelet 50 or rivet 43 while being in electrical connection with the conducting strip 42 is normally at its outer end free from all the metallic parts connected with the casing 10. The 55 conducting strip 33 is always in electrical connection with the housing or escutcheon 27, and the conducting strip 42 is normally out of electrical connection with said housing or escutcheon and the metal parts connected therewith. When it is desired to 60 make a circuit through the lamp and battery the push-button 32 may be pushed inwardly to press the spring 30 against the eyelet or rivet 43, the end portion of said spring 30 65 being always opposite to the outer end of said eyelet or rivet, and when a more permanent light is desired, the thumb-piece 31 of the switch mechanism may be pushed upwardly, in the present instance, so as to carry a bent end 45 of the switch spring 30 against the 70 eyelet or rivet 43 so as to complete the circuit without the aid of the push-button 32. The movement of the spring 30 against the eyelet 43 establishes electrical connection between the conducting strip 42, housing 27 75 and conducting strip 33 in a manner which will be well understood without detailed explanation. The rivet or eyelet 47 by means of which the lower end of the escutcheon or housing 27 is secured against the side of the 80 casing 10, has its inner end within an enlarged hole 48 in the conducting strip 42, and hence said conducting strip is, at the eyelet or rivet 47, insulated from the housing or escutcheon 27. To aid further in producing 85 a structure which will not be subject to accidental circuiting, the sleeve 15 is set upwardly from the lower edge of the casing 10 so that by no possibility can the disk 36 get into electrical connection with 90 said sleeve. The invention resides more particularly in the manner of securing and mounting the conducting strip 42 and in the construction within the cap 13 to cooperate with the 95 strip 42, which, as shown in Fig. 2, extends slightly below the lower edge of the casing 10. The construction as a whole has been designed with the view of avoiding accidental circuiting through the battery and 100 lamp, and to accomplish this result by means and combinations which are positive in the performance of their functions. 105 I may also add that when the cap 13 is screwed downwardly to a slight extent sufficient to carry the metal plate 36 from the conducting strip 42, the circuit cannot be made through the lamp and battery even though the spring switch be operated, and this is a feature of advantage since under 110 such condition there will be no danger of the lamp being accidentally lighted when carried in the pocket or a dress-suit case by contact of the slide or push button with some article tending to move the same to 115 operative position. 115 What I claim as my invention and desire to secure by Letters-Patent, is: 1. In a battery hand lamp having on the rear end of its casing a removable cap and a conducting strip extending forwardly within and from below said casing, an insulating disk upon the inner face of said cap, a metal plate secured over said disk having a raised rim portion spaced from said cap, and a coiled spring secured on said rim portion and engaging the negative pole of the battery, said rim portion engaging the rear end of said conducting strip when said cap is applied to position, the means securing 120 125 130 135 140

said metal plate being insulated from said cap, and the means securing said spring on said rim portion being loops formed on said portion through which said spring is 5 threaded.

2. In a battery hand lamp having on the rear end of its casing a removable cap and a conducting strip extending forwardly within and from below said casing, an insulating 10 disk upon the inner face of said cap, a second insulating disk on said first mentioned disk, a metal plate secured upon said second disk and having a rim portion spaced from said cap and a coiled spring secured on said plate 15 and engaging the negative pole of the battery, said rim portion of said plate engaging the rear end of said conducting strip when said cap is applied to position.

3. In a battery hand lamp having on the 20 rear end of its casing a removable cap and a conducting strip extending forwardly within and from below said casing, an insulating disk upon the inner face of said cap and

having an opening, a second insulating disk on said first-mentioned disk, a metal plate 25 secured upon said second disk having a raised rim portion spaced from said cap, and a coiled spring secured on said rim portion and engaging the negative pole of the battery, said rim portion engaging the rear end 30 of said conducting strip when said cap is applied to position, the means securing said metal plate on said second disk being a rivet which extends through said insulating disk and plate and into the said opening in the 35 said first disk and is spaced from said cap, and the means securing said spring on said rim portion being loops formed on said portion through which said spring is threaded.

Signed at Springfield, in the county of 40
Hampden and State of Massachusetts, this
23rd day of May, A. D. 1919.

JOHN T. DRUFVA.
